United States Patent Office.

DENNIS LANE, OF MONTPELIER, VERMONT.

Letters Patent No. 86,556, dated February 2, 1869.

IMPROVEMENT IN WATER-WHEELS.

The Schedule referred to in these Letters Patent and making part of the same.

To all whom it may concern:

Be it known that I, DENNIS LANE, of Montpelier, in the county of Washington, and State of Vermont, have invented a new and valuable Improvement in Gates and Guides for Water-Wheels; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a plan view of my device, and

Figure 2 is a sectional view thereof.

The object of my invention is to construct, for use with the Jonval turbine water-wheel, a more perfect and effective gate than has heretofore been devised therefor, and also to form, in combination with such gate and wheel, suitable water-chutes for the water before it reaches the gates.

The letters A, of the drawings, represent inclined planes, or chutes, down which the water passes to the gates. They are formed by cutting out the upper surface of the wheel-casing, or, as is preferable, by casting such casing in the shape represented.

The letter B is the gate proper. It is constructed of a flat plate of metal, turned up at nearly right angles, the upright part of which fits closely against the shoulder of the chute, and the horizontal part fits to the bottom of said chute. The extreme horizontal end of said gate is rounded upward, to admit of a ready flow of water thereunder when partially raised, so as to render it an aid in raising the gate.

The letter C is a slotted guide, adjusted by a set-screw to a flange, formed on the wheel-casing, on the inner side of the opening in said casing, through which the water passes to the wheel. This flange is marked D on the drawings. By means of this guide and set-screw, the gate may be tightened in its place, or loosened, at pleasure.

These gates and guides are adjusted to the water-openings in the wheel-casing, in such manner and number that there shall be a guide and gate at each opening.

The letters E are upright rods, extending from ears, attached to the horizontal parts of the gates proper, to the rods F, next mentioned.

The rods F are connected with rods E, in the manner shown, at their lower ends, and their upper ends rest, respectively, on the arms of the sleeve G, hereinafter described. I form a screw on the upper portion of rods F, respectively extending nearly to the heads thereof, and adapt thereto nuts, as shown at a. These screws and nuts are designed for use in adjusting the position of gates B.

Letter H is a sleeve, fitting loosely around the cylinder K, that encloses the shaft of the water-wheel. It is formed with arms, extending outward, as shown, and rests upon and rotates slightly upon a shoulder in cylinder K, as represented at c.

Letter O is a rod, screwed into the surface of sleeve G, and is adapted to be united with a rope, or chain, or rod, by means of its eye d.

To open the gates, I raise the rod O, and thereby the sleeve G and all its attachments. By lowering the rod O, the gates are closed.

One important advantage secured by my device is that, by the use of the guides and set-screws, adjoining the gates, I can tighten said gates at will, whenever, from wear or other cause, it becomes important or desirable so to do.

What I claim as my invention, and desire to secure by Letters Patent, is—

A gate for the Jonval turbine water-wheel, having chutes A, gate B, guides C, flange D, with the set-screws operating therewith, rods E and F, sleeve G, and cylinder K, all constructed, arranged, and operating substantially as specified.

In testimony that I claim the above, I have hereunto subscribed my name, in the presence of two witnesses.

DENNIS LANE.
